UNITED STATES PATENT OFFICE.

THOMAS MUNGALL, OF CHICAGO, ILLINOIS.

SECONDARY ELECTRIC CLOCK.

946,148.

Specification of Letters Patent. Patented Jan. 11, 1910.

Application filed June 1, 1909. Serial No. 499,400.

To all whom it may concern:

Be it known that I, THOMAS MUNGALL, a subject of the King of England, residing at Chicago, county of Cook, and State of Illinois, have invented certain new and useful Improvements in Secondary Electric Clocks, of which the following is a specification.

My invention relates to improvements in secondary electric clocks, the object of the invention being to provide a device of this character that shall be inexpensive of manufacture, strong and durable in its construction, and of the highest possible efficiency.

A further object of my invention is to provide a movement for secondary electric clocks which shall not be liable to be too rapidly advanced under the successive impulses imparted to the driving wheel, nor be subject to a retrograde movement when the driving pawl of the movement is not imparting forward motion to the driving wheel, such provision being especially desirable in secondary clocks designed to control the movements of heavy hands, such as are employed for tower clocks.

Other objects will appear hereinafter.

With these objects in view my invention consists in the novel construction and arrangements of parts which will be herein-30 after fully described and more particularly pointed out in the appended claims.

My invention will be more readily understood by reference to the accompanying drawings forming a part of this specification, and in which,

Figure 1 is a front elevation of my improved secondary clock in its preferred form, Figs. 2 and 3 are side elevations thereof, Fig. 4 is a detail top plan view, Fig. 5 is a view showing the action of the principal mechanism of the clock movement, Fig. 6 is a detail vertical section, the driving wheel being shown in elevation, Fig. 7 is a detail vertical section taken on line α α of Fig. 3, Fig. 8 is a vertical section, and Figs. 9 and 10 are detail elevations.

Referring now to the drawings, 1 designates the driving ratchet wheel and 2 the driving pawl adapted to mesh therewith and to impart a step by step motion thereto. The driving pawl 2 is pivoted to a radially extending arm 3 by means of the screw 4, said arm being rotatably mounted on the central arbor 5. The pawl 2 is provided with a recess 6 on the side thereof opposite the ratchet wheel 1, and the armature lever 7 of

the electro-magnet 8 is adapted to engage said recess for impelling the pawl forward when the line circuit from the central clock (not shown) is closed, said electro-magnet being included in said line circuit. The armature lever 7 is suspended in such a manner that when the same is drawn toward its magnet into the position as indicated by dotted lines, the pawl 2 will assume the dotted line position and be held in close engagement with the teeth of the ratchet wheel to prevent movement thereof as long as the circuit is kept closed, the block 9 integral with the armature lever 7 adapted to engage the pawl 2 at the point 10 for holding the latter in this position. When the circuit is opened and the armature lever 7 released, then the pawl 2 is free to disengage one tooth of the ratchet wheel 1 and to be moved backward sufficiently to engage the next tooth thereof, the adjustable stop screw 11 being provided to limit the movement of said armature lever.

It will be seen that the armature lever 7 when in the dotted line position nearly coincides with a straight line connecting the central arbor 5 and the pivot 12 of the armature lever 7, and that the clearance between said lever and the pawl 2 is secured when these members are in the full line position. The block 9 acts as a stop for limiting the upward movement of the pawl 2 and for holding the same in engagement with the teeth of the ratchet wheel 1, as aforesaid, but it is obvious that the lower edge of the armature lever 7 might contact with the bottom of the recess 6 for accomplishing the same purpose. The dog 13 secured to the arbor 14 is adapted to be held in normal engagement with the teeth of the ratchet wheel 1 to prevent retrograde movement of the same when the pawl 2 is moving backward from one tooth to another. A radial pin 15 is secured to the arbor 14, and to said pin one end of a tension helical spring 16 is attached, the other end of the latter being attached to the screw 4. This spring embraces the periphery of the drum 17 which is secured to a member of the frame 18 by means of the screws 19 and whose axis coincides with that of the central arbor 5, the functions of said spring being to hold the dog 13 in normal engagement with the teeth of the ratchet wheel 1, and to hold the pawl 2 in the normal or full line position. The driving ratchet wheel 1 is pressed securely onto the central arbor 5, one end of the latter being

journalized in the frame 18. A ratchet wheel 20 disposed inside of the drum 17 is provided with a sleeve 21 which is rotatably mounted on the arbor 5, on which sleeve the 5 spur gears 22 and 23 are mounted, the former being rigidly secured to said sleeve and the latter being free to rotate thereon. The seconds hand 24 is secured to the central arbor 5, the minute hand 25 to the sleeve 21 of 10 the ratchet wheel 20, and the hour hand 26 to the sleeve 27 of the gear 23, the latter gear being driven by the pinion 28 integral with the gear 29, which is driven by the gear 22.

15 To provide the proper movement of the ratchet wheel 20 without a regular gear reduction, means are provided to rotate the same to the extent of one tooth once at each revolution of the ratchet wheel 1, said means 20 comprising a catch lever 30 having a dog 31 at one end thereof for engaging the notch 32 and a dog 33 at the other end thereof for engaging the tooth of the ratchet wheel 20. This catch lever is pivoted on one side of 25 the ratchet wheel 1, and the dog 31 is held normally in sliding contact with the stationary internal surface 34 of the drum 17 by means of the spring 34' secured to the ratchet wheel 1 ready to engage the notch 32 when it 30 registers therewith, the dog 33 engaging the ratchet wheel 20 simultaneously with the last named movement. The ratchet wheel 20 is rotated to the extent of one tooth, then the dog 31 is thrown out of engagement with 35 the notch 32 by means of the curved surface 35 sliding over the corner 36 of the drum 17.

Various slight changes might be made in the general form and arrangement of parts described without departing from my invention, and hence I do not restrict myself to the precise details set forth, but consider myself at liberty to make such changes and alterations as fairly fall within the spirit and scope of the claims.

45 Having described my invention what I claim as new and desire to secure by Letters Patent is:

1. In a device of the class described, a seconds hand arbor journalized in a frame, a minute hand sleeve rotatably mounted on 50 said arbor having a ratchet wheel integral therewith, a drum secured to said frame whose axis coincides with the axis of said ratchet wheel, an hour hand sleeve mounted 55 on said minute hand sleeve and means for rotating the same, a notch in the inner surface of said drum, a catch lever pivoted to

a side of the drive ratchet wheel secured to said arbor, resilient means connected with said catch lever whereby the same is adapted 60 to engage said notch and said first named ratchet wheel for rotating the latter to the extent of one tooth, and means for releasing said catch lever, substantially as described.

2. In a device of the class described, a 65 seconds hand arbor journalized in a frame provided therefor, an arm rotatably mounted on said arbor having a pawl pivoted thereto at its outer extremity, a recess in said pawl on the side thereof opposite said arbor, 70 a pendent magnet armature lever adapted to engage said recess in said pawl and to advance the same when the magnet is energized, a block integral with said armature lever adapted to engage said pawl and to 75 hold the same in engagement with said ratchet wheel when the pawl is in its advanced position, resilient means for returning said pawl to its normal position, means for preventing retrograde movement of said 80 ratchet wheel, a drum secured to said frame whose axis coincides with said arbor, a minute hand ratchet wheel adapted to receive intermittent motion from said first named ratchet wheel having a sleeve integral therewith and rotatably mounted on 85 said arbor, an hour hand gear mounted on said sleeve, and means for driving the latter, substantially as described.

3. In a device of the class described, a 90 ratchet wheel secured to an arbor, journalized in a frame provided therefor, a seconds hand attached to one end of said arbor, a radial arm rotatably mounted on said arbor, a pawl pivoted to the outer extremity of said 95 arm adapted to engage the teeth of said ratchet wheel, a recessed portion in said pawl, a pendent magnet armature lever adapted to engage said recessed portion and to advance said lever when the line circuit 100 is closed, said pawl when advancing being adapted to rotate said ratchet wheel, means to prevent retrograde movement of said ratchet wheel, and means connected with said ratchet wheel for imparting intermittent 105 motion to the hour and minute hands of the clock, substantially as described.

In testimony whereof I have signed my name to this specification in the presence of two subscribing witnesses.

THOMAS MUNGALL.
